UNITED STATES PATENT OFFICE

ARNO HEMPEL, OF CHICAGO, ILLINOIS

DESIGN FOR A LIGHTING FIXTURE

Application filed June 5, 1930. Serial No. 35,911. Term of patent 3½ years.

To all whom it may concern:

Be it known that I, ARNO HEMPEL, a citizen of Germany, residing in Chicago, county of Cook, and State of Illinois, have invented a new, original, and ornamental Design for a Lighting Fixture, of which the following is a specification, reference being had to the accompanying drawing, forming a part thereof.

Fig. 1 is a front view of the lighting fixture;

Fig. 2 is a perspective view thereof, and
Fig. 3 is a top plan view.

I claim:

The ornamental design for a lighting fixture as shown.

ARNO HEMPEL.
